UNITED STATES PATENT OFFICE.

ANTHONY A. FROEHLINGSDORF, OF ST. PAUL, MINNESOTA.

CHECK-STUB HOLDER.

1,414,269.

Specification of Letters Patent. Patented Apr. 25, 1922.

Application filed October 30, 1920. Serial No. 420,740.

To all whom it may concern:

Be it known that I, ANTHONY A. FROEHLINGSDORF, a citizen of the United States of America, residing at St. Paul, in the county

5 of Ramsey and State of Minnesota, have invented certain new and useful Improvements in a Check-Stub Holder; and I do hereby declare the following to be a full, clear, and exact description of the invention, such as 10 will enable others skilled in the art to which it appertains to make and use the same.

The object of the invention is to provide a simple, inexpensive and efficient means for holding the stubs of a check book out of 15 the way so as to expose the stub of the check which is being made out and more especially to secure the used stubs in an out-of-the-way position when there are two or more checks on the same page of the book, or to hold

20 pages of the check book in an out-of-the-way position when a number of checks are being made out in succession and are not being torn out or detached from the book as they are made out, so that the stub belonging 25 to each check may be exposed to facilitate the endorsement thereof, and in fact to provide a device for holding certain pages or leaves of a book of any kind out of the way or in a folded back position while writing

30 upon an exposed page at an intermediate portion of the book, the device being particularly applicable to account books, ledgers and the like which are of large size and which must be retained in a substantially 35 flat position upon the desk or table while endorsements are made upon the pages thereof or while making entries or transcribing accounts, striking balances, etc.; and with these objects in view the invention consists

40 in a construction and combination of parts of which a preferred embodiment is shown in the accompanying drawing, wherein:—

Figure 1 is a view of the holder embodying the invention applied in the operative 45 position to a book of the check book type.

Figure 2 is a sectional view on line 2—2 of Fig. 1.

Figure 3 is a perspective view thereof detached from the book.

50 Figure 4 is a plan view of the blank from which the holder is formed.

The device consists essentially of a separator bar 10 carrying a curved wing 11 which in the construction illustrated is of 55 looped form embodying a transverse member 12 and arcuate arms 13 for engaging and restraining the book stubs or leaves 14,

and a retaining arm 15 for engagement with the flat leaves of the book to maintain the holder in proper position to restrain the 60 stub leaves.

The separating bar 10 carries spurs 17 consisting of tapered tongues for engagement with the binding of the book, and the retaining arm is preferably provided with an 65 upstanding ear or flange 19 to reinforce the same and facilitate manipulation of the flat leaves of the book.

In practice it is preferred to construct the holder of a single plate or sheet of metal of 70 which the blank is shown in Figure 4, folded upon the dotted lines shown to form the dividing bar and flange 19, the tongues forming the spurs being struck out from incisions 20 at the bases of the arcuate arms 13. 75

The book being opened at the point indicated, it will be seen that the holder may readily be applied thereto and crowded up against the rolled surface of the outermost stub leaf and then drawn downward to engage the retaining arm with the edges of 80 the flat leaves of the book so that it is firmly locked in position, and the flat exposed page of the book may then be maintained in a flat condition while entries are made thereon 85 or while the checks are being made out without necessitating the holding of the stubs in place by hand as in the ordinary practice.

The upstanding ear or flange of the retaining bar forms a convenient handle or grip 90 by which the holder may be manipulated, and the flat bearing of the retaining bar upon the surface of the exposed page retains the same in proper position while affording a suitable support for the holder. 95

Having thus described the invention, what I claim is:—

A book holder comprising a wing to maintain the used stubs raised from the unused stubs, a single stub engaging arm extending 100 therefrom adjacent one end to engage the unused stubs adjacent the top thereof whereby the view of the unused stubs below said arm will be unobstructed by the holder, and a flange extending along the upper edge of 105 said arm and at right angles thereto to act as a reinforcement and hold the device in position on the book.

In testimony whereof I affix my signature in presence of two witnesses.

ANTHONY A. FROEHLINGSDORF.
